PENCIL SHARPENING DEVICE

Jodie Fred Gilliam, Barberton, Ohio

Application June 26, 1945, Serial No. 601,633

8 Claims. (Cl. 120—95)

1

This invention relates generally to a pencil sharpening device and pertains particularly to a device of the semi-automatic type.

A principal object of the present invention is to provide a pencil sharpening device designed to be mounted upon a fixed support and wherein the movement of a cutter around the inserted end of the pencil is brought about by the movement of the pencil itself in a circular path.

Another and more specific object of the invention is to provide a pencil sharpening device of the type designed to be mounted upon a fixed support, wherein there is provided a circular chamber having a rotatable end wall through which the end of the pencil is extended in eccentric relation with the rotatable wall, into a rotary cutter supported in the casing, means being provided in association with the rotary cutter for frictional contact with the circular wall of the casing whereby rotation is imparted to the cutter upon the movement of the pencil and rotatable wall around a fixed center.

The invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a view in front elevation of a pencil sharpening device constructed in accordance with the present invention.

Figure 2 is a vertical section, on an enlarged scale taken substantially on the line 2—2 of Figure 1.

Figure 3 is a detail section on an enlarged scale through the cutter, wheel and pencil guide.

Figure 4 is a partial section taken substantially on the line 4—4 of Figure 2.

Referring now more particularly to the drawing the numeral 10 generally designates a circular housing which has the circular side wall 11, the fixed back wall 12 and the disk-like front wall 13.

Formed integrally with the back wall 12 is a 50

2

tubular guide or sleeve 14 to receive a mounting screw 15.

The back wall 12 also is provided with a number of points or spurs 16 for engagement in the surface against which the sharpener is secured so as to prevent turning of the housing around the mounting screw 15.

The front wall 13 of the housing forms a closure or cap and is provided with a central opening 17 in which the forward end of the sleeve 14 engages. The sleeve 14 forms a pivot post for the cap or front wall 13 so that the latter may rotate in the housing, and the head of the mounting screw functions to retain the cover or wall 13 in position upon the sleeve.

In that portion of the housing 10 which is lowermost when the housing is mounted, there is provided a shavings discharge opening 18 and there is detachably mounted upon the underside 20 of the housing, the receptacle 19 to receive shavings from the opening 18. Any suitable means may be employed for mounting the receptacle 19 in position such, for example, as the resilient clips or fingers 20 which have their opposing faces engaged by the ribs or flanges 21 carried by and extending across the opposite sides of the receptacle.

Formed through the rotatable cover wall 13 adjacent to the periphery thereof, is a pencil receiving opening 22 and upon the inner side of the wall 13 there is fixed concentrically with the opening 22 the tubular guide 23, a portion of the inner end of which is of reduced diameter as indicated at 24, to form an arbor 25.

Fixed to the inner side of the rotatable wall 13, as at 26, is a bracket arm 27 which extends inwardly away from the wall 13 and terminates in a bearing eye 28 which is concentric with the opening 22 and with the arbor 25.

40 The numeral 29 designates a tubular axle which receives in one end the arbor 25 upon which it rotates. The opposite end of this axle is tapered to form the conical cutter shell 30, the wall of which is provided with a number of spirally directed slots 31 each of which is bordered along one edge by the inwardly directed cutting blade 32.

The conical cutter member 30 terminates in the stem 33 which has bearing engagement in

Encircling the tubular axle 29 is the wheel 34, the periphery of which engages the inner surface of the circular wall 11 as a result of which when the wall 13 is turned around the tubular sleeve 14, rotary motion will be given to wheel 34 and to the tubular axle and cutter so that an end of an inserted pencil, extended through the tubular axle into the conical cutter unit 30, will be shaved off into a point by the blades 32 and the shavings will drop into the bottom of the housing and pass into the receptacle 19.

The arbor 25 is interiorly tapered toward its free end as indicated at 25a and there extends through the major portion of the guide 23 and the arbor forming the inner end of the guide, a tubular collar 35 which is tapered and which is slit through the major portion of its length from its inner end.

The outer end of the collar 35 has formed therearound a flange 36 and encircling the collar between this flange 36 and a shoulder 37 formed upon the inner side of the guide 23, is the coil spring 38 which normally urges the sleeve 35 outwardly toward the opening 22 thereby disengaging the tapered inner end from the tapered inner wall 34 of the arbor.

Outward movement of the tubular collar under the action of the spring is limited by the tubular insert 23a which is fixed in the outer end of the tubular guide 23 as shown.

Secured to the inner side of the wall 13 is an arm 39 which carries a brush 40. This brush is arranged so that it will have the bristles engage the inner surface of the wall in advance of the periphery of the wheel 34 to thus keep the surface of the wall, in advance of the wheel, free from shavings.

In the use of the present device the pencil is inserted into the opening 22 and extended into the tapered, split sleeve 34. As it is then thrust farther in, the sleeve 35 will be shifted against the tension of the spring 38 until it snugly engages the pencil and it is, itself, snugly engaged in the tapered portion of the arbor and the pencil is then slid through into the tapered or conical unit 30 in which the cutter blades are formed. The tapered sleeve 35 holds the pencil against lateral or wobbling movement and after the pencil has been introduced in the manner stated it is used in the nature of a crank to impart turning movement to the wall 13. As the wall 13 rotates around the sleeve 14 the wheel 34, having peripheral contact with the inner side of the circular wall 11, will be rotated, thus turning the cutting blades so as to cut away the wood of the pencil and form a tapered point thereon in the usual manner of pencil sharpeners.

From the foregoing it will be seen that the device herein described provides a relatively simple and easily operated means for quickly sharpening a pencil and such device is so designed that it may be economically constructed and is strong and durable.

I claim:

1. A pencil sharpener comprising a casing having a circular inner wall, a disk-like wall closing said casing and supported for rotation on an axis concentric with said circular wall, the disk-like wall having an eccentric opening for the reception of a pencil, a pencil guide within the casing and concentric with the opening, a tubular axle rotatably supported on said guide, a tapered pencil sharpener unit forming an axial extension of the inner end of the tubular axle to receive the end of a pencil inserted through the guide and

4
axle, and a wheel carried by the tubular axle and having peripheral contact with said circular wall to impart turning movement to the cutter unit upon the turning of the disk-like wall around the said axis.

5. 2. A pencil sharpener of the character stated in claim 1, with a bearing bracket secured to the inner side of the disk-like wall and connected with and providing a bearing support for the inner end of the sharpener unit.

15 3. A pencil sharpener of the character stated in claim 1, with means supported within the tubular guide for limited axial movement therein and adapted to grip an inserted pencil by the axial movement of the pencil inwardly to maintain the pencil centered in the tubular guide and against lateral movement.

20 4. A pencil sharpener of the character stated in claim 1, with a longitudinally split tubular sleeve supported in said guide, means limiting axial movement of the sleeve in the guide, the sleeve and guide at their inner ends being tapered whereby the sleeve, when moved inwardly in the guide, will be contracted about an inserted pencil, and spring means normally urging movement of the sleeve outwardly away from the tapered inner end of the guide to release the pencil.

25 5. A pencil sharpener of the character stated, comprising a housing having a circular inside wall surface, a sleeve forming an integral part of the housing and extending axially therethrough, a disk-like wall closing an end of the housing and supported for turning movement around the sleeve, said disk-like wall having an eccentric pencil receiving opening, a tubular pencil guide secured to the inner side of the disk-like wall concentric with the opening and formed at its inner end to provide an arbor, a bracket secured to the inner side of the disk-like wall and carrying a bearing, a tubular axle having one end receiving and rotatably mounted on the arbor and having its other end formed to provide a conical pencil sharpener unit and a stem at the apex of said unit, said stem being rotatably supported in the bracket bearing, and a wheel carried by and concentric with the tubular axle and having its periphery contacting the circular wall of the housing.

30 6. A pencil sharpener of the character stated in claim 5, in which said arbor is interiorly tapered at its free inner end, a sleeve member disposed within the pencil guide and arbor and having its inner end tapered for extension into the tapered portion of the arbor, the said inner end 35 of the sleeve being longitudinally split for the reduction of the sleeve diameter at its inner end, means forming an outwardly facing shoulder inside the guide, said sleeve having a flange upon its outer end in opposed relation with the shoulder, 40 and a coil spring encircling the sleeve between the flange and shoulder and normally urging movement of the sleeve outwardly toward the pencil receiving opening.

35 7. A pencil sharpener of the character stated in claim 5, with a brush unit supported upon the inner side of the disk-like wall and contacting the circular inner wall surface in advance of the wheel for the removal of shavings therefrom.

40 8. A pencil sharpener as set forth in claim 6, 70 in which said arbor is interiorly tapered at its free end, a sleeve member disposed within the pencil guide and arbor and having its inner end tapered for extension into the tapered portion of the arbor, the said inner end of the sleeve being 75 longitudinally split for the reduction of the

sleeve diameter at its inner end, means forming an outwardly facing shoulder inside the guide, said sleeve having a flange upon its outer end in opposed relation with the shoulder and a coil spring encircling the sleeve between the flange and shoulder and normally urging movement of the sleeve outwardly toward the pencil receiving opening, and a brush member supported upon the inner side of the disk-like wall and having operative connection with the periphery of the wheel 10 to keep the latter free of shavings.
